CLAIM

The ornamental design for a packaging container as shown and described.

DESCRIPTION

FIG. 1 is a top perspective view of a packaging container showing my new design;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown in the drawings illustrate portions of the packaging container that form no part of the claimed design.

1 Claim, 8 Drawing Sheets(56)
